Wm P. Cresson, David Stuart, Jacob Beesly, & Samuel M. Sailor (designated
by Wm P. Cresson.) Philad^a Penn^a
Letters Patent (Design No 88) dated 3^d October 1846

The schedule referred to in these Letters Patent and making part of the same.

To all whom it may concern:

Be it known that

No. 10m P. C. L. S. David Stuart, Jacob Beesly and Sam'l H. Taylor, all of the County of Philadelphia in the State of Pennsylvania, have invented a new and useful set of designs to ornament cast-Iron Stove plates, which when put together forms the body of a Stove and oven, all of which when set upon a Stove Base, forms a Crooking stove, or said plates or designs may be used in or to ornament a variety of stoves in connection with other plates, and do hereby declare that the following is a full and exact description of the particular plates which we wish to Patent.

The general form of the stove, when complete, as now laid out will be a cylindrical body to make and contain fire in, with door-sight for purposes of regulating the fire, and an oblong square oven on top with folding doors in front, but the ornamental designs may be laid out on Stoves of any variety or form.

The plates which we wish to patent, the particular arrangements of ornaments on each, as well as the designs we wish to patent are fully represented in the accompanying drawings viz:

Plate 1. Fig. 1. Represents the front plate of the oven, with leaf work ornamenting the edges and sides, and head work running around near the inner edges, to receive the doors, with ornamented sockets, near each corner to receive the hinges of the doors, we do not now mean to claim the separate ornaments on this stove plate, but the particular arrangement of them on this plate.

Fig. 2. Represents the bottom plate of the oven, the particular ornamental edge work of which we claim as original and wish to patent. Represented A. A. A. A.

Plate 2. Fig. 2. Represents one of the doors, the ornamental design in the centre of which being a very rich bouquet of flowers we claim as originals and design to patent.

Fig. 3. Represents the side plates, the ornamental design in the centre representing fancy bird heads, tied together with a ribbon each holding a bouquet of flowers in its beaks, as well as their necks being partially covered with leaf work, and their bodies hidden by a rich

display of flower work.

Fig. 4. Represents the back plate of the oven, the centre of which is richly laid out in flower wheel work the edges of which will be found to represent Horns of Plenty with bouquets of flowers represented as flowing from each towards the centre which is entirely filled with flower wheel work.

Fig. 5. Represents the front plate of the body of the stove with the door intended to regulate the fire in its proper place, the lower space of the plate is ornamented with flower sprout work, as represented. A, the door ornaments the upper part of the plate and is ornamented with flower sprout work as represented B.

Fig 6. Represents the side & back plates of the body of the stove, it is ornamented in the centre with a flower stand almost wholly covered with flowers, which extend up and ornament the whole space in the centre of the plate.

We have thus detailed the particular ornamental designs on the respective plates, which we wish to patent and do hereby claim the exclusive right to the said ornamental designs for stone plates, as we have laid them out and displayed them on the body of a stove, and oven.
